UNITED STATES PATENT OFFICE.

THOMAS HIPWELL, OF ALLEGHENY, PENNSYLVANIA, ASSIGNOR TO THE
PITTSBURGH BRASS COMPANY, OF SAME PLACE.

LAMP-HANGER.

SPECIFICATION forming part of Letters Patent No. 443,521, dated December 30, 1890.

Application filed June 25, 1890. Serial No. 356,658. (No model.)

To all whom it may concern:

Be it known that I, THOMAS HIPWELL, a resident of Allegheny city, in the county of Allegheny and State of Pennsylvania, have 5 invented a new and useful Improvement in Lamp-Hangers; and I do hereby declare the following to be a full, clear, and exact description thereof.

My invention relates to harps or hangers 10 for lamps—that is, to a device for the suspension of a lamp from a ceiling or suitable bracket.

The object of my invention is to provide a 15 suspension device in which the lamp-fount, together with the chimney supported thereon, may be inserted within the hanger without having to tilt or incline said fount or chimney, thus removing the liability of the breaking 20 or cracking of the chimney by having the flame come in contact therewith on the tilting of the same, cracking of the chimney by striking the shade, or spilling the oil from the fount.

A further object is to provide a hanger 25 which will support the fount firmly in position and prevent any liability of its dropping when roughly handled or jolted.

To these ends my invention comprises, generally stated, a lamp-hanger having a ring at 30 the base thereof, lugs formed on the interior face of said ring at opposite points, and a spring-bail having arms engaging with said lugs and extending out beyond the same for the support of the fount resting in said ring.

To enable others skilled in the art to make 35 and use my invention, I will describe the same more fully, referring to the accompanying drawings, in which—

Figure 1 is a side view, partly in section, 40 of my improved hanger supporting the lamp. Fig. 2 is a bottom view of the supporting-ring. Fig. 3 is a top view showing spring-arms in engagement with the lugs. Fig. 4 is a section on the line 4-4, Fig. 3; and Figs. 5 45 and 6 are detail views showing the two positions of the bail.

Like letters indicate like parts.

The hanger *a* is shown formed of wire bent to proper shape and having a hook or loop *b* 50 at the upper end thereof to engage with a

suitable hook or loop secured to the ceiling or bracket. At the base of the hanger *a* is the ring *c*, said ring being formed with the inwardly-extending flange *d* at the upper edge thereof. On the lower edge of the ring *c* and 55 on the interior face thereof are formed the lugs or cams *e*, at points directly opposite each other, and each on the same side of the central line of the ring. The lugs *e* are rounded off, as at *f*, and are also provided 60 with the small indentations, as at *g*, forming a slight shoulder, for the purpose more fully hereinafter set forth. A slight enlargement *h* is formed on the exterior of the ring *c* just beyond the lugs *e*, and within said enlargement is formed the recess *i*, in which the arm *k* of the spring-bail *j* rests when not engaging 65 with the lugs *e*. The bail *j* is formed of stiff spring-wire and bent to the semicircular form, its ends being bent at substantially 70 right angles to the bail to form the arms *k*, and the journals *l*, which are bent at substantially right angles to the arms *k*, being journaled in the bearings *m* in the enlargements *h* and at the upper ends of the recesses *i*. If 75 desired, a second auxiliary bail *n* may be employed to strengthen the support given by the bail *j*, the said auxiliary bail *n* being journaled, as at *o*, in the ring *c*, and being further provided with the loop *p*, adapted to engage 80 with the bail *j*.

To provide for the supporting of the fount of the lamp within the hanger it has been customary to construct said founts with a shoulder or annular flange encircling said 85 fount at its point of greatest circumference, this flange being shown at *r*, and in the ordinary harp this flange resting on top of the harp-ring.

To insert the fount within the hanger *a* the 90 bail *j* and its auxiliary bail *n* will be raised to the position shown in Fig. 2, when the fount carrying the chimney may be raised by a direct vertical movement into the ring *c* until the annular flange *r* on said fount comes in 95 contact with the inwardly-extending flange *d* of the said ring, which retards further upward movement of the fount. The fount is held in this position by one hand while the bail *j* is grasped by the other, when by a quick 100

movement of the hand enough force is exerted to overcome the resistance to the arms *k* due to the lugs *e*, whereby said spring-arms travel over the faces of the lugs *e* and assume the horizontal position shown in Figs. 1, 3, 4, and 6. The rounded faces *f* aid to render the movement of the spring-arms *k* over said lugs more easy, and said arms having passed said lugs spring back to the position above said lugs, but project far enough beyond said lugs to give a firm support to the fount, the lower face of the annular flange *r* thereof resting on the arms *k*, which are supported on the lugs *e*. The shoulders *g* form an abutment for the portion of the bail just beyond the arms *k* and further assist to render the engagement secure against any violent shaking or handling of the hanger. In this manner the fount is locked within the ring *c* without having to tilt the fount or chimney in the slightest degree, and as the upper edge of the annular flange *r* bears against the flange *d* and the arms *k* bear against the lower face of the flange *r* the lamp is firmly held against upward or downward movement in the ring. The bail *j* also serves as a handle for the raising or lowering of the hanger, the tension of the spring-bail and its arms *k* being sufficient to prevent liability of displacement of said bail in ordinary handling.

To further supplement the resistance of the bail *j* to lateral movement, the auxiliary bail *n*, which is mounted at right angles to the bail *j*, may be lowered, the loop *p* thereof engaging with the bail. To remove the fount, the operator grasps the bail *j*, and by applying force enough to overcome the resistance due to the shoulders *g* the arms *k* resume their former vertical position within the recesses *i*, removing all obstructions to the lowering of the fount from the ring *c*, and it can then be lowered directly from the ring.

What I claim as my invention, and desire to secure by Letters Patent, is--

1. In a lamp-holder, the combination, with the hanger, of a ring at the base thereof, a bail journaled in the ring, and cam mechanism for contracting the bail, so that the bail when so contracted forms a support for the fount, substantially as and for the purposes set forth.

2. In a lamp-holder, the combination, with the hanger, of a ring at the base thereof, said ring having lugs formed on the interior face thereof at opposite points thereon, and a bail journaled in the ring and provided with arms engaging with said lugs and extending beyond the same for the support of the fount, substantially as and for the purposes set forth.

3. In a lamp-holder, the combination, with the hanger, of a ring at the base thereof, said ring having an inwardly-extending flange at the upper edge thereof, and lugs formed on the lower edge of said ring at opposite points thereon, and a bail journaled in said ring having arms engaging with said lugs and extending beyond the same for the support of the fount, substantially as and for the purposes set forth.

4. In a lamp-holder, the combination, with the hanger *a*, of the ring *c*, having the flange *d*, lugs *e*, and recesses *i*, and the bail *j*, having the arms *k* at an angle to the bail, substantially as and for the purposes set forth.

5. In a lamp-holder, the combination, with the hanger *a*, of the ring *c*, having the lugs *e*, the bail *j*, having the arms *k*, and the auxiliary bail *n*, having the loop *p*, substantially as and for the purposes set forth.

In testimony whereof I, the said THOMAS HIPWELL, have hereunto set my hand.

THOMAS HIPWELL.
